CLAIM

The ornamental design for a portable handset radio telephone, as shown and described.

DESCRIPTION

FIGS. 1 and 2 are respectively front and rear elevational views of a portable handset radio telephone showing my new design in slidably extended position; FIGS. 3 and 4 are respectively left and right side elevational views thereof;

FIGS. 5 and 6 are respectively top and bottom plan views thereof;

FIG. 7 is a cross-sectional view taken on line VII—VII in FIG. 1 with interior construction omitted;

FIG. 8 is a front, top and right side perspective view thereof;

FIG. 9 is a front, top and right side perspective view with the handset in closed position; and

FIG. 10 is a front, top and right side perspective view in extended position of a second embodiment thereof corresponding to FIG. 8, with the differences in this embodiment vis-a-vis the first being showing of the handset telephone in operative condition with antenna raised, and with the display panel, and sundry pushbuttons bearing typical operative indicia.

The broken line showing of numerals in the display panel in FIG. 10 is for illustrative purposes only and forms no part of the claimed design.
